FIG. 1.

FIG. 2.

To all whom it may concern:

Be it known that we, Richard D. Grayson and Le Roy Newton, citizens of the United States, residing respectively at La Canada, county of Los Angeles, California, and Monrovia, county of Los Angeles, California, have invented a new, original, and ornamental Design for a Water-Heater Control, of which the following is a specification, reference being had to the accompanying drawing, forming a part hereof.

Figure 1 is a perspective view of a water-heater control embodying our new design; and

Figure 2 is a left end elevation of the structure shown in Figure 1.

The dominant features of the design reside in the portions shown in full lines.

We claim:

The ornamental design for a water-heater control, substantially as shown and described.
